ATTORNEY

UNITED STATES PATENT OFFICE.

JEREMIAH MARTONE, OF WATERBURY, CONNECTICUT.

ATTACHMENT FOR GRINDING MACHINES.

Application filed November 14, 1925. Serial No. 69,068.

This invention relates to cutter grinding machines, and more particularly to a holding device for guiding a spiral milling cutter while its teeth are being ground.

5 One object of this invention is to provide a device of the above nature which may be attached to the stationary bed of a grinding machine, and which will guide each of the teeth of the cutter in succession and cause them to 10 be ground uniformly without removing the attachment from the machine.

A further object is to provide a work-holding attachment for a grinding machine which will have a double universal joint for rotary 15 adjustment and means for allowing longitudinal adjustment.

A further object is to provide a device of this nature which will be simple in construction, inexpensive to manufacture, easy to install and manipulate, compact, and very efficient and durable in use.

With these and other objects in view there has been illustrated on the accompanying drawings, one form in which the invention 25 may be conveniently embodied in practice.

Fig. 1 represents a side view in elevation of a grinding machine upon which the improved attachment has been installed.

Fig. 2 is a side sectional view of the same, 30 shown partly in section.

Referring now to the drawings, in which like reference numerals denote corresponding parts throughout the several views, the numeral 10 indicates the sliding lower table of a grinding machine, said table 10 being adapted 35 to rest on a rotary bed, not shown, said bed being capable of vertical and rotatable movement with respect to the machine base, not shown.

40 The rotary grinding wheel 11 is rigidly mounted on the base of the machine by means not shown and is constructed in saucer-shape form. The grinding wheel 11 is carried by a shaft 12, the latter being driven by any suitable source of power, not shown. The top of the grinding wheel is protected by a semi-circular guard member 13.

A sliding upper table 14 is mounted upon the lower table 10, and is adapted to be reciprocated longitudinally by manually-controlled means, not shown. The sliding upper table 14 supports at its ends a pivoted head stock 15 and a rigid tail stock 16, between the centers 17 and 18 of which a mandrel or arbor 55 19 is supported. The arbor 19 serves to sup-

port the work to be ground, which in this instance comprises a milling cutter 20 having spiral teeth.

In order to hold the tooth being ground in parallel contact with the grinding wheel, while the milling cutter is reciprocated back and forth, a work-holding attachment is provided, and will now be described.

The work-holding attachment comprises a flat pedestal 21, adapted to be rigidly secured, 65 as by a screw bolt 22, to the lower table 10 of the machine. Upstanding from the pedestal 21 is a vertical post 23 which is preferably formed integral with said pedestal. A rod 24 is mounted to have rotative adjustment 70 on a vertical as well as on a horizontal axis. For this purpose, a lower clamping block 25 is slidably held on said vertical post 23, as by a bolt 26 and nut 27, said lower block 25 having a projecting member 28 for slidably 75 supporting the rod 24.

Slidably mounted on the top of the rod 24 is an upper clamping block 29 similar to the lower block 25, previously described. The upper block 24 has a pair of clamping jaws 80 30 and 31 adapted to be tightly held upon a work-holding arm 32 by means of a bolt 33 and nut 34. A micrometer adjusting mechanism 35 is provided for moving the work-guiding finger 36 toward and away from the milling cutter 20. The micrometer mechanism 35 is adapted to be manipulated by a knurled knob 37. The finger 36 is preferably made with a slightly curved extremity 38 which is adapted to fit against the tooth next to the one being ground. The rear portion of the finger 36 is secured as by a screw 39 to a strip member 40, resiliently mounted within a box member 41 within which it is free to vibrate 90 on a pivot pin 42. 95

The rear of said strip member 40 is pressed by a spring 43 which permits the finger to yield and release chips or other materials which might otherwise cause the cutter to be injured. The spring 43 also allows the finger to be bent up about its pivot to permit the cutter to be rotated until the finger is in alignment with the next tooth without disturbing the adjustment of the work-holding attachment. 100

In operation, when it is desired to grind the teeth of the milling cutter, the work-guiding finger 36 will first be adjusted to fit into the tooth next to the first one to be ground. The proper angle of inclination correspond- 105 110

ing to the pitch of the spiral cutter is obtained by manipulation of the double universal joint described above. The rotary bed will next be raised until the cutter is adjacent the grinding wheel which is stationary at this time, and the face of the tooth will be brought into parallel contact with the face of the grinding wheel. The operator will then lower the rotary bed until the cutter is out of contact with the grinding wheel, and the power will then be turned on to rotate the grinding wheel at high speed. The thickness of cut will then be accurately gauged by turning the micrometer knob 37 to move the cutter the required angular distance toward the grinding wheel. To obtain the first cut, the operator will raise the cutter the required distance and will slide the upper table and cutter along the grinding wheel until the entire length of the tooth has been cut. The same cut will then be taken from all of the other cutter teeth. For the second cut the cutter will be raised again still further and the operation repeated on all of the teeth. This process will be repeated until the desired depth of each tooth has been ground.

One advantage of the present invention is that the work-guiding finger may be positioned at any conceivable angle or height. 30 A further advantage is that the depth of cut may be adjusted after the correct angular position has been obtained and the former adjustment is independent of the latter. Moreover, this construction permits the cutter to be fed toward the grinding wheel with-

out the use of a transversely fed table, which was formerly required.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claim.

Having thus fully described the invention, what is claimed as new, and for which it is desired to secure Letters Patent, is:

In a work-holder for guiding a spiral milling cutter while the latter is being ground by a rotating grinder, a vertical post adapted to be held stationary upon the lower table of the machine, a lower clamping block slidable vertically upon said post and carrying an adjustable inclined arm, means for holding said inclined arm in adjusted position, an upper clamping block slidably and rotatably mounted on the upper part of said inclined arm, a horizontal work-guiding finger carried by said upper clamping block, means in front of said upper block for minutely adjusting said work-guiding finger toward and away from the work.

In testimony whereof, I have affixed my signature to this specification.

JEREMIAH MARTONE.
